UNITED STATES PATENT OFFICE.

RICHARD J. OLDFIELD, OF PHOEBUS, VIRGINIA.

SWING.

1,107,341.

Specification of Letters Patent. Patented Aug. 18, 1914.

Application filed August 21, 1913. Serial No. 785,860.

To all whom it may concern:

Be it known that I, RICHARD J. OLDFIELD, a citizen of the United States, residing at Phoebus, in the county of Elizabeth City 5 and State of Virginia, have invented certain new and useful Improvements in Swings, of which the following is a specification.

This invention relates to swings and more particularly to the class of swings known as 10 porch swings wherein the swing is suspended from a ceiling or other overhead support.

The primary aim of the invention is to produce a swing in which the back-rest thereof is self-adjusting to accommodate 15 itself to the position desired by the occupant, means being provided whereby the back-rest can be readily fastened in any position desired to retain the same stationary relatively to the seat.

Another object of the invention is to provide an improved foot-rest and support 20 therefor which permits the foot-rest to be self-adjusting.

With the above and other objects in view 25 the invention contemplates improvements in the seat, back-rest, foot-rest, and suspending means whereby the parts of the swing may be self-adjusting to suit the convenience and comfort of the occupant; facilitate swinging movements, and also to so form the rear 30 suspension that the same yieldably connects the back-rest and seat, to give a spring-effect to the back, and further, to provide fastening means which are a part of the rear suspension so that the back-rest may be held 35 stationary relative to the seat.

In carrying out the objects of the invention as generally stated above it will be readily understood that the essential features 40 thereof are necessarily susceptible to changes in details and structural arrangements, a simple and preferred embodiment thereof being shown in the accompanying drawings, wherein—

Figure 1 is a perspective view of the improved swing. Fig. 2 is a side view thereof, dotted lines being used to indicate the back-rest in an inclined position.

The improved swing forming the subject 50 matter of this invention, in its preferred embodiment, comprises a seat 1; a back-rest 2, the lower edge of which has hinge connections 3 with the rear of the seat 1; and a foot-rest 4 that has the rear ends of its side 55 bars 5 pivotally connected to the lower ends of hangers 6 detachably connected to and

depending from the front portions of the side bars 7 of the seat 1, the hangers 6 being reinforced by the diagonal braces 8 that connect the said bars 7 and said hangers 6. 60 Side guards 9 are provided for the seat, and said guards carry the flat arm-rests 10.

The swing, as described, is formed of wood, and the seat, side-guards, foot-rest and back-rest, are preferably formed of, or 65 include, spaced, parallel slats which afford simple, convenient, and ornamental ventilating and draining facilities.

The side bars 11 of the back-rest 2 each have a laterally projecting arm 12 fastened thereto, the arms being preferably of metal and having enlarged ends fastened to the bars. The arms 12 overlap the outer sides 70 of the side guards 9 and are curved on the arc of the circle upon which the back-rest 75 swings, and their outer, or free, ends are provided with longitudinally extending slots 13, through which thumb-screws 14 carried by the side guards project. At their intermediate portions the arms 12 are enlarged to 80 provide the upper and lower ears 15 and 15'.

The outer surface of each side bar of the seat 1 is provided at its front and rear end 85 portions with upstanding straps 16 and 17, respectively, which terminate at their upper ends in the hooks 18 and 19. The hooks 18 engage the end rings 20 of the front suspending chains 21 that depend from the porch ceiling or other overhead support, and the hooks 19 are engaged by the end 90 rings 22 of the short chains 23 that depend from the lower ears 15' of the arms 12. The upper ears 15 of the arms 12 are connected to the ceiling or other overhead support by 95 the rear suspending chains 24.

The front ends of the outer surfaces of the side bars of the foot-rest 4 carry hooks 25, to which the lower ends of the rings 26 of the front suspending chains 27 are connected.

It will be observed that the swing is suspended by means of the chains 21, 24—23, and 27, and the arms 12, and that as said arms 12 connect the chains 23—24 and are carried by the back-rest 2, the said back-rest is normally held from a rearwardly inclined position by the chains 23—24, and when the seat is occupied and the occupant desired to recline, outward movement of the back-rest is yieldably opposed by said chains 110 23—24. In other words, the chains 23—24 have a spring-effect on the back-rest that op-

poses movement of the back-rest away from the seat, and that therefore the back-rest automatically adjusts itself to the position desired by the occupant. It will also be 5 clear, that the arms 12 serve as levers which coöperate with the chains 23-24 to facilitate swinging movements. Normally the thumbscrews 14 serve as guides for the arms or levers 12, but when desired, said thumb-screws can be readily tightened to clamp 10 the levers 12 to the side-guards and thereby retain the back-rest stationary relative to the seat 1.

The manner of connecting the chains to 15 the hooks 18, 19, and 25, obviously permits the necessary pivotal movements, and also facilitates attaching or detaching the chains from said hooks. And the described pivotal connection of the foot-rest 4 with the 20 seat 1, through the hangers 6, permits the necessary relative movements of the foot-rest to the seat 1.

It will be observed that the hangers 6, braces 8, foot-rest 4 and seat 1 are connected by means of bolts, such connections permitting the parts to be readily separated when desired so that packing or shipping of the swing is facilitated. It will also be observed that the hangers 6 are connected by 30 means of slats which are designated by the numeral 28, thus forming guards for the skirts of the occupant.

What I claim as my invention is:—

1. A swing comprising a seat provided 35 with rigid sides, a back-rest hinged thereto and provided with laterally projecting lever arms that overlap the sides of the seat, said lever arms being provided with longitudinal

slots adjacent their free ends, suspending chains connected to intermediate portions 40 of the lever arms, chains connecting intermediate portions of the lever arms with the rear of the seat, front suspending chains for the seat, and clamping means carried by the sides of the seat and projecting through the 45 slots in the lever arms.

2. A swing comprising a seat, a back-rest hinged thereto, laterally projecting lever arms rigidly fastened to the back-rest and overlapping the sides of the seat, suspending cables for the front of the seat, suspending cables connected to intermediate portions of the lever arms, cables connecting intermediate portions of the lever arms to the seat, and means carried by the sides of 50 the seat for clamping the lever arms thereto.

3. A swing comprising a seat, a back-rest hinged thereto, laterally projecting lever arms carried by the back-rest and overlapping the sides of the seat, said arms having 60 upper and lower oppositely disposed laterally projecting intermediate ears and having longitudinal slots in their free end portions, suspending cables for the front of the seat suspending cables engaging the upper 65 ears of the lever arms, cables connecting the lower ears of the lever arms with the seat, and clamping means carried by the sides of the seat and projecting through the slots in the lever arms.

In testimony whereof I have affixed my signature in presence of two witnesses.

RICHARD J. OLDFIELD.
